CONDITION CONTROLLER

Mark C. Honeywell, Wabash, Ind., assignor to
 Minneapolis-Honeywell Regulator Company,
 Minneapolis, Minn., a corporation of Delaware

Application April 29, 1938, Serial No. 205,135

3 Claims. (Cl. 297—1)

This invention relates in general to automatic controllers, and is more particularly concerned with automatic controllers of the type employing elongated flexible condition responsive material such, for instance, as humidity controllers.

The primary object of this invention is the provision of a controller of this type which is simple and compact in construction, which is accurate in operation, which may readily be assembled to provide any desired differential or operating range of the instrument, and in which the responsive element may be readily replaced when necessary.

The above results are obtained by the provision of a rotatable drum upon which the condition responsive material is wound, the condition responsive material being secured at one end to the drum, and at its other end to a fixed support, to thereby cause rotation of the drum upon change in value of the condition to which the material responds. This rotation of the drum in turn is utilized to actuate a control device for thereby changing the position of said control device in accordance with changes in value of said condition.

A more specific object of this invention, therefore, is the provision of a condition controller of the type mentioned with a rotatable drum upon which the condition responsive material is mounted, and in which the rotary motion of the drum resulting from change in value of the condition is utilized for actuating a control device.

Other objects of this invention will become apparent from the following description and the appended claims.

For a full disclosure of my invention, reference is made to the following detailed description and to the accompanying drawing, in which

Figure 1 is a perspective of my improved humidity controller, showing the instrument lying on its base plate, and in which

Figure 2 is an elevational view partly in section.

Referring to the drawing, reference character 1 indicates the base plate for the instrument. This base plate may be mounted upon a wall or any suitable support for the instrument. Mounted upon the base plate by means of posts 2 and 3 is a bracket member 4, this bracket member being formed to provide ears 5 and 6 which project inwardly as shown. The bracket member 4 forms a support for a rotatable drum 7, this drum being carried by a pin or shaft 8 which is secured to the bracket member. The drum 7

may be formed in any suitable manner and is shown as comprising front and rear plates 9 and 10 which are secured together at the center or hub of the drum. Mounted between the front and rear plates 9 and 10 are rollers 11, 12, and 13 which may be supported by suitable pins extending between these plates. The rollers 11, 12, and 13 are spaced around the drum as indicated and provide support for an elongated humidity responsive device or element 14. This humidity responsive element may consist of a plurality of strands 15 of hair or other moisture responsive material, these strands being secured together at one end by means of a clamping member 16 and at the other end by means of a clamping member 17. The clamping member 17 is secured to a suitable cross piece extending between the plates 9 and 10. The strands 15 pass from this clamping member 17 over the rollers 12, 13 and 11 to the clamping member 16 which is secured by a link 18 to an adjusting screw 19 which is carried by the ear 6 of bracket member 4. The adjusting screw 19 is provided with a head 20 and with an adjusting nut 21. The head 20 is urged away from the ear 6 by means of a spring member 22 which is secured to the ear 6. This spring member 22, therefore, urges nut 21 against ear 6 at all times. By this arrangement, it will be apparent that rotation of the adjusting nut 21 will cause movement of the adjusting screw 20 transversely of the ear 6, thereby changing the position of the clamping member 16.

A spring 23 is attached at one end to a clip 24 carried by the rotatable drum 7, and the other end of this spring is attached to the ear 5 of bracket member 4. This spring serves to urge the drum 7 in a counter-clockwise direction to thereby maintain the strands 15 of the humidity responsive element taut at all times. Upon change in relative humidity, the strands 15 change in length. For instance, if the humidity responsive element is formed of strands of hair, this material will increase in length as the relative humidity increases. This increase in length of the strands 15 will permit counter-clockwise rotation of the drum 7 due to the action of the spring 23. Upon decrease in relative humidity, however, these strands will decrease in length thereby causing rotation of the drum 7 against the action of the spring 23.

Reference character 25 indicates a U-shaped bracket which may be mounted upon the base plate 1 or upon any suitable support. Pivotedly mounted in the bracket 25 is a lever arm 26, this lever arm being provided with an ear 27 which is

adapted to engage a pin 28 carried by the drum 7. This lever arm is also provided with a spring 29 for urging the arm upwardly so as to maintain the ear 21 in engagement with the pin 28.

- 5 3 Lever arm 26 at its extremity carries a baffle member 30 which is adapted to engage a bleed port 31 which is mounted in a hollow projection 32 secured to the base plate 1. This hollow projection may be provided with an opening plugged 10 by a plug 33 for permitting insertion and removal of the bleed port element 31.

It will be apparent that as the drum 7 rotates in a counter-clockwise direction due to a change in relative humidity, the pin 28 will move downwardly and this downward movement of the pin 28 will cause downward movement of the lever 26, this causing movement of the baffle member 30 away from the bleed port member 31. This will increase the rate of bleed through the bleed port 20 and consequently decrease the pressure in the control system in a manner well understood in the art. Upon clockwise rotation of the drum 7, however, the pin 28 will move upwardly thereby permitting upward movement of the lever 26 by 25 the spring 29, this causing the baffle 30 to approach the bleed port member 31 and increase the pressure within the pneumatic control system to which the instrument is applied.

It will be apparent that by changing the location of the pin 28 on the drum 7, the ratio of movement of drum 7 to movement of lever 26 may be varied. Thus if the pin 28 is moved nearer to the center of the drum 7, there will be less movement of lever 26 for a given movement of drum 7 than will occur with the pin 28 in the position shown. Thus by merely changing the position of the pin 28 upon the drum 7, the operating range or differential may be readily varied. If desired, the pin 28 instead of being 40 fixedly secured to the drum 7 may be adjustably secured thereto so as to permit readily adjustment of the range of the instrument.

It will be noted that with the construction above described, the drum 7 and the humidity 45 responsive element may be removed from the instrument as a unit. This arrangement makes replacement of the humidity responsive element a very simple matter even when the instrument is in a relatively inaccessible location.

50 60 From the foregoing description, it will be apparent that this invention provides a simple and compact humidity controller and further provides a controller which may readily be assembled to provide any desired operating range or differential. While I have shown and described a preferred form of my invention, it will be understood that many modifications of my invention will become apparent to those skilled in the art. I, therefore, desire to be limited only by the scope 55 of the appended claims.

I claim as my invention:

1. In a condition controller, in combination, a drum member, mounting means for said drum member including a bearing for permitting rotation of said drum member in a plane normal to said bearing, a plurality of rollers mounted upon said drum member, said rollers being spaced 65

from each other and having axes of rotation parallel to said bearing, elongated condition responsive material wound around said drum member and riding upon said rollers, said material being adapted to change in length upon change in the 5 condition to which it responds to thereby cause rotary movement of said drum member upon change in value of said condition, a control device, and means actuated by rotary movement of said drum member for actuating said control 10 device.

2. In a condition controller, in combination, a rotatable member, mounting means for said member including a bearing for permitting rotation of said member in a plane normal to said bearing, said mounting means providing for ready removal and replacement of said member, an elongated condition responsive element wound around said rotatable member in the plane of rotation of said member, said element being 15 adapted to change in length upon change in value of the condition, having one end attached to the rotatable member and its other end attached to a relatively stationary support for thereby causing rotary movement of said rotatable member upon change in value of said condition, the major portion of said element being wound upon said rotatable member and extending 20 around said rotatable member substantially 25 a full turn so that the element is almost entirely supported by said rotatable member, said rotatable member including spaced supporting means for said element for permitting free circulation of fluid about all sides of the portion of the element carried by said rotatable member, a control device, and means actuated by rotary movements of said rotatable member for actuating 30 said control device.

3. In a condition controller, in combination, a rotatable member, mounting means for said member including a bearing for permitting rotation of said member in a plane normal to said bearing, said mounting means providing for ready removal and replacement of said member, an elongated condition responsive element wound around 40 said rotatable member in the plane of rotation of said member, said element being adapted to change in length upon change in value of the condition, having one end attached to the rotatable member and its other end attached to a relatively stationary support for thereby causing 45 rotary movement of said rotatable member upon change in value of said condition, the major portion of said element being wound upon said rotatable member and extending around said rotatable member substantially a full turn so that the element is almost entirely supported by said rotatable member, said rotatable member including spaced supporting means for said element for permitting free circulation of fluid about all sides 50 of the portion of the element carried by said rotatable member, a control device including a lever adjacent said rotatable member, and a pin carried by said rotatable member and abutting 55 said lever for causing movement of said lever upon rotation of said rotatable member.

MARK C. HONEYWELL.
